Patented Dec. 21, 1920.

William E. Kelly.

b. f. Heinkel - Atty

UNITED STATES PATENT OFFICE.

WILLIAM E. KELLY, OF CLEVELAND, OHIO.

ARBOR.

1,362,872.

Specification of Letters Patent. Patented Dec. 21, 1920.

Application filed March 10, 1919. Serial No. 281,768.

To all whom it may concern:

Be it known that I, WILLIAM E. KELLY, a citizen of the United States, residing at Cleveland, in the county of Cuyahoga and State of Ohio, have invented a new and useful Arbor, of which the following is a specification.

My invention relates to arbors for holding objects or articles while operations are performed thereon.

10 The object of my invention is to provide an arbor which can receive certain objects and articles readily and economically, upon which objects and articles can be adjusted either concentrically or eccentrically, and upon which the centers can be adjusted to accommodate different classes of operations.

Heretofore it has been a constant source of expense and loss of time to form objects, 20 other than round, upon an arbor as for instance backing off flat cutters or providing clearance thereon which is accomplished in a very economical and satisfactory manner with the present invention.

25 I attain my object by certain mechanism, one application of which is illustrated in the accompanying drawings which show an arbor for flat cutters and in which Figure I is a plan view of an arbor adapted to grind flat cutters; Fig. II is a side elevation of Fig. I; Fig. III is a section on line 3—3 of Fig. II; Fig. IV is an end elevation at 4 of Figs. I and II showing normal positions of centers; Fig. V is also an end elevation at 35 4 showing the centers in an adjusted position; Fig. VI is a plan view of a portion of a cutter grinder arbor showing one modification; Fig. VII is an end elevation of Fig. VI; and Fig. VIII is an end elevation of a 40 bushing showing the centers in a certain position.

Similar reference characters refer to similar parts throughout the several views.

In this specification I will describe the 45 apparatus shown in the drawings as adapted to hold a flat cutter while the same is being ground.

Referring now particularly to Figs. I, II, III, IV, and V.

50 The body 1, conveniently made of suitable material, has the end-portions 2 and 5 which have suitable slots in their ends into which the center blocks 6 and 7 fit slidingly.

In the bottom of these slots and in proper 55 position, these end-portions 2 and 5 have a tapped opening into which the clamp-

screws 8 and 9 fit for the purpose of clamping the center-blocks in position. The central portion of the body 1 is formed as shown; there being a slot 10, the face 11 of 60 which, preferably, is located below the longitudinal axis of the body. This slot 10 is adapted to accommodate the cutter which is being held on the body. Adjacent to the slot 10 and transversely thereto, the body 1 is provided with the slot 13 which accommodates the adjusting-block 14. It will be seen that the slot 13 is somewhat wider than the block 14 for the purpose of permitting the same to move laterally and permit of 65 adjustment of the cutter. Adjacent to the slot 13 and on each side thereof, the body 1 has a tapped opening into which the adjusting-screws 15 fit for the purpose of adjusting the cutter 16 upon the body 1. Adjacent to the slot 10 and opposite the slot 13, the body 1 has the portion 17 which projects above the longitudinal axis of the body. This portion 17 has the opening 18 into which the clamp-screw 19 fits. To prevent 70 the clamp-screw 19 from turning, the pilot-screw 20 is tapped into the body 1 in proper position. To provide means for partially or wholly rotating the body 1, the handle 21 is screwed into the body 1 as shown. 75

The center-blocks 6 and 7, made of suitable material, fit slidingly into the slots in the end portions 2 and 5 as hereinbefore stated and are provided with the ears 22 which have tapped openings to receive the 80 adjusting-screws 23 which are provided for the purpose of adjusting the center-blocks in relation with the body 1. The center-blocks have the centers 24 which coincide with the zero mark 0 thereon and also have 85 the centers 25 which are located off center as clearly seen in Figs. IV and I. On one edge and along the central portion, the center-blocks 6 and 7 have division-marks or 90 graduations whereby the amount of clearance to be given or ground on the cutter 16 may be determined positively and without experimentation while the cutter is being ground. The graduations may be spaced and marked in any convenient manner; for 95 instance, the mark A may indicate a cutter two inches in diameter, the mark B three inches and so forth and the graduations intermediate these lettered marks, three between each lettered mark, will indicate two 100 and one quarter, two and a half and two and three quarter inches, the object being to 105 110

have a definite mark to set the apparatus to for each size of cutters whereby experimentation is avoided and all cutters are ground with proper clearance and much time and expense saved. The off-centers 25 are provided for relieving or breaking the corners 26 and are spaced according to the angle to be given this face 26 as will appear hereinafter.

10 The adjusting-block 14 is located in the slot 13 which is wider than the block to permit of side-wise adjustment thereof and projects into the slot 10. That portion of the block 14 which so projects into the slot 10 should fit the usual centering-notch 27 in the cutter 16.

15 The screw 19 is provided to clamp the cutter 16 in adjusted position by means of the clamp-plate 28 and is provided with the slot 12 which engages the pilot on the pilot-screw 20 for the purpose of preventing rotation of the screw 19 when the nut thereon is turned.

20 The clamp-plate 28, operated by the screw 19, is provided to clamp the cutter 16 down firmly upon the body 1.

25 The operation of the apparatus so far described is as follows: The cutter 16, after being hardened, and provided with the centering-notch 27 and is otherwise ready to be ground, is now placed in the slot 10. The clamp-plate 28 is then placed thereon as seen in Fig. II and the screw 19 is now slightly tightened whereby the cutter 16 is

30 lightly held upon the body 1. The adjusting-screws 15 are now manipulated to bring the cutter 16 to a desired position either concentric or eccentric. When the cutter is in desired position, the clamp-plate 28 is

35 tightened down firmly by means of the screw 19. We will now assume that the cutter 16 is to be circular ground as the first grinding operation. For this purpose the center-blocks 6 and 7 are manipulated, 40 through the screws 23, until the zero-marks 0 on the end of portions 2 and 5 coincide with the zero-marks 0 on the center-blocks 6 and 7. When both center-blocks are so ad-

45 justed, the inner ends of all of the screws 23 should bear against the end-portions 2 and 5 so that the center-blocks can not move transversely of the body. When the screws 23 are properly set, the screws 8 and 9 are tightened. The screws 23 adjust the center-blocks 6 and 7 and also hold the same in ad-

50 justed position sidewise while the screws 8 and 9 clamp the same against the bottom of the slots in the end-portions 2 and 5.

55 The apparatus is now ready to circular grind the cutter 16 to the light line L as seen in Fig. IV; by rotating the apparatus partly or wholly on the centers 24, either by means of a machine or by means of the handle 21.

60 After the cutter is circular ground, it is

necessary that the same be backed off to provide cutting clearance which is necessary in all cutters. In order to accomplish this, in an easy and quick manner, the present invention shifts the centers so that an easily and 70 economically accomplished circular movement of the apparatus will produce a uniform and proper and positively determined cutting clearance on the cutter.

75 We will now assume that the cutter to be backed off is two and three quarter inches in diameter. As stated hereinbefore, the graduation-mark A on the cutter-blocks 6 and 7 represents a cutter two inches in diameter and the mark B represents a cutter three 80 inches in diameter. There being three lines or four spaces between lines A and B, therefore, each line between A and B represents one quarter of an inch of diameter or, in other words, the line A represents two inches 85 in diameter, the first line from A toward B two and one quarter inches, the second line from A toward B two and one half inches, the third line from A toward B two and three quarter inches, and the next line, B, 90 three inches as stated.

95 In order to set the center-blocks 6 and 7 to properly back off the two and three quarter inch cutter, the screws 8 and 9 are loosened slightly. The adjusting-screws 23 are then manipulated until the third graduation-line, from A toward B, on the center-blocks coincide with the zero line 0 on the end of the portions 2 and 5 as seen in Fig. V. When the center-blocks are so adjusted, the 100 inner ends of the screws 23 should bear firmly against the end-portions 2 and 5 to prevent lateral movement of the center-blocks and the screws 8 and 9 are then tightened to firmly lock the center-blocks in 105 position.

110 The face 29 of the cutter 16 is now brought in contact with a grinding-wheel and the apparatus as a whole partially rotated, back and forth, on the centers 24 whereby this face 29 will be backed off as seen in Figs. III and V. The cutter is then reversed on the body and the face opposite 29 is backed off in a similar manner.

115 Most cutters require some relief at the cutting point 26. In order to produce this relief, the centers 25 are provided and are spaced a suitable distance from the centers 24 but preferably in line therewith. In order to relieve a cutter properly it is preferred that the centers be shifted as was done in backing off. For that reason the center-blocks 6 and 7 should be adjusted as was done in backing off. It should be noted here that, in relieving a cutter, the apparatus 125 is rotated on the center 25 in the center-block 6 and on the center 24 in the center-block 7. With this arrangement, a line drawn through the centers 25 and 24 will be inclined to the axis of the apparatus and a 130

grinding-wheel brought against the point 26 will relieve the same at a determined angle and provide proper clearance thereon. When one point of the cutter is so relieved, 5 the cutter is reversed on the body and the opposite point is relieved in like manner.

When a comparatively large number of cutters of one size are to be ground, the more simple but non-adjustable arrangement 10 shown in Figs. VI, VII, and VIII may be preferred to the arrangement shown in Figs. I, II, III, IV, and V.

This arrangement consists of the body 31 which has the end-portions 32 which are 15 bored out to receive the bushings 33 which are held in position and prevented from turning by the pilot-screws 34 which are tapped into the end-portions 32. Only one end of the apparatus is shown on the drawings, the other end is a duplicate of the one shown. The parts and members not shown in these views are similar to the parts and members shown in Figs. I to V.

The bushings 33 fit slidingly but rather 25 close into the bored openings in the end-portions 32 and have the slots 35 which engage the pilots of the screws 34 to prevent rotation of the bushings as well as to hold the same in proper relative position. With 30 this arrangement, it is preferred and may be necessary that sets or pairs of bushings are provided to accommodate different sizes of cutters, all of the bushings should fit properly into the openings provided for that 35 purpose in the ends of the end-portions.

For circular-grinding and relieving the cutter 16, hereinbefore described, with this arrangement, a pair of bushings are provided which have the centers 36 and 37 in 40 each bushing; the centers 36 as well as the centers 37 being located axially opposite each other or in other words: the centers 36, one in each end, coincide when viewed from the end of the arbor; likewise the centers 37. 45 For relieving a cutter, as also hereinbefore described, a pair of bushings are provided which have the centers 39 and 41 in each bushing; the centers 39 as well as the centers 41 being located axially opposite each 50 other similar to the centers 36 and 37.

Owing to limited space, the drawings are not quite as clear as they might be but should be comprehensive in connection with the particular explanation given.

To operate this apparatus, the bushings 33 are placed into their respective openings and held there by the screws 34. To circular-grind a cutter, the apparatus is rotated on the centers 36. To back off a cutter, the apparatus is rotated on the centers 40 and 41. To relieve a cutter, the appara-

tus is rotated on the centers 39 and 41. The operations not described in detail here are similar to the operations previously described.

65

The bushings 33 as well as the center-blocks 6 and 7 may be eliminated when cutters of a few sizes only are to be ground continuously; the pairs of centers may, in that case, be drilled directly into the ends of the body. In this instance, one arbor may accommodate two or more sizes of cutters and separate pairs of centers may be provided on the body for each size of cutter.

70

This arrangement is more limited since only a few sizes of cutters can be accommodated on one arbor while the arbors formerly described will accommodate a comparatively large number of cutters.

80

It will be seen that this invention provides an economical, efficient, and positive mechanism for grinding cutters as well as other articles and operations of a similar nature and conduces to considerable saving 85 of time and labor.

Therefore, without limiting myself to the precise construction shown and described,

I claim:

1. An apparatus of the character described having a body, center-blocks mounted on said body, means for adjusting an article upon said body, and means for clamping said article upon said body.

90

2. An apparatus of the character described comprising a body, a center-block mounted on each end of said body, a plurality of centers in said center-blocks, means for holding the said center-blocks in position, means for adjusting an article upon said body, and means for holding said article upon said body.

95

3. An apparatus of the character described having a body which is provided with a surface on one side to fit an article 100 and with a plurality of pairs of centers, and means for holding said article upon said surface.

105

4. An apparatus of the character described having a body which is provided 110 with a plurality of pairs of centers, means for adjusting an article upon said body, and means for clamping said article upon said body.

5. An apparatus of the character described having a body, a pair of center-blocks mounted on said body, each center-block provided with a plurality of centers, and means for holding an article upon said body.

115

WM. E. KELLY.
